COVER OF CYCLE AND LIKE SADDLES

Herbert Franke, Muhlhausen, Germany; vested
in the Alien Property CustodianApplication July 1, 1939, Serial No. 282,374
In Germany August 16, 1938

5 Claims. (Cl. 155—5.23)

Heretofore in saddle covers for this purpose the construction of the cover comprises a fabric of flax or similar coarse yarns which is vulcanized to rubber or a rubber compound. The purpose of this construction is to give the saddle cover both perfect tensile strength and also great elasticity, as the tensile strength against tearing depends upon the fabric insert and the elasticity upon the rubber foundation.

In these known constructional forms the embedded insert consists in general of a fabric of flax or other loosely interwoven yarns extending through the entire cover. It is evident that a construction of this kind possesses the drawback of having comparatively little elasticity, as the relatively tight weaving of the fabric puts a limit to its resiliency.

Now, there have been special constructional forms which aim at increasing the elasticity of the cover by giving the fabric insert or the yarns constituting the same a special form. For instance, the fabric has been made so loose in weaving that the yarns were able to be displaced with respect to one another. Moreover, in order still further to increase the elasticity, constructional forms have been produced in which the warp and weft yarns do not lie in the longitudinal and transverse axes of the saddle cover, the fabric insert being in fact embedded diagonally of the rubber foundation.

Due to the latter constructional form there is apparently a greater elongation when the saddle is under load, as the yarns are not stretched longitudinally so that the rubber foundation is not hindered in its expansion. In this case the fabric is pulled apart diagonally so that the warp and weft yarn carry out a movement in the manner of shear legs.

In all these constructional forms the elongation of the fabric has put a limit to the elongation of the saddle cover although it was intended to obtain a particularly supple cover by means of the rubber foundation.

In my present invention I provide reinforcements of fabric or equivalent material in a saddle cover of rubber or similar resilient material in such a manner that reinforcements from opposite sides or ends are not directly connected to each other but are intermeshed or otherwise arranged and connected through the rubber of the cover. The reinforcements are preferably embedded and vulcanized in the rubber material. They are connected by the rubber in a zone in the centre of the cover which is free from fabric. Further there are arranged transversely

5 of this central zone between the edges of the fabric inserts, one or more rubber beadings which produce a reinforcement of the cover at this point, where it is not reinforced by the canvas insert.

The invention is illustrated by way of example in the accompanying drawing, in which

Fig. 1 is an inverted plan view of an embodiment of the invention, seen from below.

Fig. 2 is a section on the line C—D of Figure 1.

Fig. 3 a section on the line A—B of Figure 1.

Figs. 4, 5 and 6 are inverted plan views of modified forms of the invention.

In Figure 1 a designates a fabric strip which is vulcanized into the rear edge of the cover, and b is a further fabric strip vulcanized into the front edge of the cover; c are rubber beadings for reinforcing the rubber portion in order to eliminate the risk of tearing the centre portion of the cover, where no fabric strip has been inserted. This rubber beading c extends from the front to the rear fabric insert and is preferably approximately in the shape of a cigar, so that the thickest part lies approximately in the centre of the saddle cover, where the risk of tearing the cover is greatest.

Now, when the saddle is placed under load, there is nothing to hinder its elongation at the portion where there is no fabric insert as there is no fabric there to oppose this elongation. But due to the insertion of the fabric a tearing of the rubber transversely of the direction of elongation is avoided.

Figures 4 to 6 illustrate further constructional forms. In these, the fabric strips a, b are provided with extensions d which may mesh with one another in the manner of a comb, so that the tearing line, if the rubber should tear transversely of the direction of elongation, would have to be substantially longer than the straight transverse tearing line, and this almost entirely eliminates the danger of tearing. In this manner the saddle attains high tensile strength without at the same time losing any of its requisite elasticity, as the fabric insert does not form one continuous whole from back to front of the cover but is composed of a front and a back strip which in this special manner are connected only by the intervening rubber.

As illustrated in Figures 4 to 6, several rubber beadings may of course be used in the control zone of the saddle.

What I claim and desire to secure by Letters Patent of the United States is:

1. A cover for cycle saddles comprising a sheet

of rubber formed to fit the saddle, a fabric strip vulcanized into the narrow front part of said cover, a further separate strip of fabric vulcanized into the wide rear part of said cover and inwardly directed tongues formed on the said strips, said tongues intermeshing in spaced relationship with each other.

2. The article of claim 1 in which said sheet of rubber material is provided with a local thickened ridge between said fabric strips.

3. The article of claim 1 in which a number of spaced ridges are formed in said rubber sheet extending between and overlapping the fabric strips to strengthen the sheet between said strips.

4. A cycle saddle of the type described which comprises a sheet of rubber material, a fabric strip extending from one edge of said saddle and imbedded in said rubber, and a second fabric strip extending from another edge of said saddle 20 a distance short of that required to reach said

first fabric strip, said fabric strip being imbedded in said rubber sheet and connected thereby with said first fabric strip and said rubber material being thickened locally between said fabric strips to strengthen the spaces between said strips.

5. A cycle saddle of the type described which comprises a flexible fabric strip conforming to the cantle of the saddle and extending forwardly thereof, a fabric strip conforming to the pommel of the saddle and extending rearwardly thereof a distance short of the cantle fabric to provide a space between said fabrics, and a sheet of rubber material covering and imbedding said 10 fabric strips and spanning the distance between said strips, said rubber sheet having ridges on the underside extending from one of said fabrics to the other to strengthen the rubber between said fabrics.

HERBERT FRANKE.
